DESIGN FOR A CORNER-BRACKET FOR BED-FRAMES.

SPECIFICATION forming part of Design No. 30,066, dated January 24, 1899.

Application filed November 12, 1898. Serial No. 696,307. Term of patent 3½ years.

To all whom it may concern:

Be it known that I, JAMES H. DYETT, a citizen of the United States, residing at Buffalo, in the county of Erie and State of New York, 5 have invented and produced a new and original Design for a Corner - Bracket for Bed-Frames, of which the following is a specification, reference being had to the accompanying drawings, making a part thereof.

10 My invention relates to the shape or configuration of a corner-bracket for bed-frames employed for supporting a bed - bottom of woven wire or other material in a bed or other similar structure where such a frame may be 15 useful.

In the accompanying drawings, Figure 1 is an end elevation showing my new design. Fig. 2 is a side elevation of the same, and Fig. 3 is a plan view of the same.

20 As shown in the drawings, the leading or material feature of my design consists in the corner-bracket comprising the curved neck C, terminating in the plate D, the plate E, substantially perpendicular to the plate D, and the bracket F, lying in a plane perpendicular to D and E and intersecting the neck C and plate E along their bilaterally-symmetrical axes, and the projection G, substantially rectangular in cross - section, all being as shown in the accompanying drawings. 25

Having described my invention, what I claim as new, and desire to secure by Letters Patent, is—

The design for a corner-bracket for bed-frames, substantially as shown and described. 35
